UNITED STATES PATENT OFFICE.

JOHN H. LUDWIG, OF NEW YORK, N. Y.

DESIGN FOR A PIANO-CASE.

No. 38,608.

Specification for Design.

Patented June 4, 1907.

Application filed May 2, 1907. Serial No. 371,549. Term of patent 3½ years.

To all whom it may concern:

Be it known that I, JOHN H. LUDWIG, a citizen of the United States, and a resident of New York city, borough of the Bronx, State of New York, have invented a new, original, and ornamental Design for Piano-Cases, of which the following is a specification, reference being had to the accompanying drawings, forming part thereof.

The figure is a perspective view of a piano case showing my new design.

I claim:—

The ornamental design for a piano case, as shown.

JOHN H. LUDWIG.
